[57] CLAIM

The ornamental design for a computer floppy disk drive lock, as shown and described.

DESCRIPTION

FIG. 1 is a front isometric view of a computer floppy disk drive lock according to the invention;
FIG. 2 is a rear isometric view thereof;
FIG. 3 is a front view thereof;
FIG. 4 is a left side view thereof;
FIG. 5 is a right side view thereof;
FIG. 6 is a bottom view thereof, the top view being a mirror image of the bottom view; and,
FIG. 7 is a rear view thereof.
